UNITED STATES PATENT OFFICE.

WALLACE L. COOK AND GEORGE W. RODORMER, OF CHICAGO, ILLINOIS.

PROTECTIVE DEVICE.

1,122,575.

Specification of Letters Patent.

Patented Dec. 29, 1914.

Application filed October 23, 1913. Serial No. 796,773.

To all whom it may concern:

Be it known that we, WALLACE L. Cook and GEORGE W. RODORMER, citizens of the United States, residing at Chicago, in the county of Cook and State of Illinois, have invented a certain new and useful Improvement in Protective Devices, of which the following is a full, clear, concise, and exact description, reference being had to the accompanying drawings, forming a part of this specification.

Our invention relates to protective devices and has for its object the provision of an improved device of this character which combines in a simple structure a lightning arrester and a pair of fuse elements to be used preferably in connection with low current systems.

Our invention contemplates the provision of a very simple structure for readily removing and inserting fuse elements and also an improved lightning arrester constructed so that the parts are mounted closely together to occupy a minimum amount of room.

We will explain one form of carrying out our invention more in detail by referring to the accompanying drawing in which:

Figure 1 is a top view of a protective device constructed in accordance with our invention; Fig. 2 is a sectional view on line *a—a* of Fig. 1; Fig. 3 is a sectional view on line *b—b* of Fig. 1, and Fig. 4 is a detail perspective view of one of the mounting springs.

In the illustration we show an insulating base 1 preferably made of porcelain or similar material which carries the mounting devices both for the lightning arrester and the fuse elements. Two fuse elements 2 and 3 are provided which are held between springs 4 and 5 respectively. The spring 5 is shown more in detail in Fig. 4 where it is shown as being provided with a longitudinal slit 6, and an enlarged portion 7 of this slit is near the upper extremity. The fuse elements are each provided with projecting fingers 8, 8 at their opposite extremities and the thickness of these fingers is such that they will be readily accommodated within the enlargement 7, but in reaching the position within this enlargement the two tines of the spring 5 must be bent apart as is readily apparent. The spring 4 has an opening 9 formed partly by punching therefrom

an extending projection 10 as shown more clearly in Figs. 1, 2 and 3. This extension 10 is provided with a notch 11 so as to more thoroughly confine the rounded extremity 8 of a fuse element. The arrangement is such that when the fuse element 3, for instance, is to be inserted, a projection 8 is first inserted into the opening 9 and thereafter this fuse element is bent downwardly so that its opposite extremity 8 is lodged within the recess 7. In thus bending down this fuse element to its final resting position, the first mentioned extremity 8 presses against the projection 10 and the spring action of this projection tends to firmly hold the fuse element in place between the springs 4 and 5. It will be readily seen that different lengths of fuse elements are readily accommodated. The springs 4 and 5 are suitably held in place by screws 12 and 13. Grooves 14, 14 are preferably provided within the base 1 to confine and aline the springs therein and to thus assist in assembling.

The lightning arrester portion of our improved device consists of a carbon block 15 suitably held in place by the bolts 16. Between this block and the base 1 a conducting plate 17 is provided carrying a connector 18. A groove 19 provided in the base alines these parts of the carbon block. It will be readily seen that the conductor 17 may be reversed so that the connector 18 may occupy a position approximately over the opening 20, if desired. Adjacent to this carbon block two serrated conducting elements 21, 21 are mounted and held in place by bolts 22. These conducting elements through the agency of the conducting plate 23 are in contact with the bolts 12 so that the conducting plates 21 are connected respectively to the two sides of the metallic circuit to be protected. The incoming wires of the circuit to be protected may of course be connected to either the bolts 12 or 13 as desired.

The extreme simplicity of the device as thus arranged and the ready assembling and displacement of the parts will be readily apparent to those skilled in the art.

Having however thus described one form which our invention may take, what we claim as new and desire to secure by Letters Patent is:

1. A device of the character described

105

110

- comprising an insulating base, a pair of tubular fuse elements mounted side by side upon said base, a pair of mounting springs for each fuse element secured to said base, 5 a conducting plate mounted upon said base centrally of said fuse elements, a carbon block secured to the top of said conducting plate, a pair of serrated conducting elements mounted upon said base on opposite 10 sides of said carbon block having an air gap between said elements and said block, and conducting elements respectively extending from said serrated elements to one of each pair of mounting springs.
- 15 2. A device of the character described comprising an insulating base provided with a pair of grooves, a pair of tubular fuse elements mounted side by side upon said base, a pair of mounting springs for each fuse 20 element secured to said base, each pair of springs being accommodated within one of the grooves aforesaid, a conducting plate mounted upon said base centrally of said fuse element, a carbon block secured to the 25 top of said conducting plate, a pair of serrated conducting elements mounted upon said base on opposite sides of said carbon block having an air gap between said elements and said block, and conducting elements 30 respectively extending from said serrated elements to one of each pair of mounting springs.
3. A device of the character described comprising an insulating base, provided 35 with three parallelly arranged grooves, a pair of tubular fuse elements mounted side by side upon said base, a pair of mounting springs for each fuse element secured to said base, the two pairs of mounting springs being 40 accommodated respectively in the outer grooves, a conducting plate mounted upon said base within the third groove aforesaid centrally of said fuse element, a carbon block secured to the top of said conducting 45 plate, a pair of serrated conducting elements mounted upon said base on opposite sides of said carbon block having an air gap between said elements and said block, and conducting elements respectively extending
- from said serrated elements to one of each pair of mounting springs.
4. A device of the character described comprising an insulating base provided with three parallelly arranged grooves, a pair of tubular fuse elements mounted side by side upon said base, a pair of mounting springs for each fuse element secured to said base, the two pairs of mounting springs being 55 accommodated respectively in the outer grooves, a reversible conducting plate mounted upon said base within the third groove aforesaid centrally of said fuse element, a carbon block secured to the top of said conducting plate, a pair of serrated conducting elements mounted upon said base 60 on opposite sides of said carbon block having an air gap between said elements and said block, and conducting elements respectively extending from said serrated elements to one of each pair of mounting springs, said 70 conducting plate being longer than said carbon block, whereby it is adapted to extend beyond said carbon block in either one direction or the other.
5. A device of the character described 75 comprising an insulating base, a pair of tubular fuse elements mounted side by side upon said base, a pair of mounting springs for each fuse element secured to said base, a carbon block mounted upon said base centrally of said fuse elements, a pair of serrated conducting elements mounted upon said base, and each located between the base and the position to be occupied by the corresponding fuse element, said serrated elements being arranged so that an air gap exists 80 between them and said carbon block, and conducting elements respectively extending from said serrated elements to one of each pair of mounting springs.
- In witness whereof, we hereunto subscribe our names this 21st day of October, 90
A. D. 1913.

WALLACE L. COOK.
GEORGE W. RODORMER.
